Term of patent 3½ years

(Cl. D83—1)

Fig. 4.

Fig. 6.

FIG. 1 is a front elevational view of an aviator's bail-out oxygen tube connection unit, showing my new design;
FIG. 2 is a right side elevational view thereof;
FIG. 3 is a bottom plan view thereof;
FIG. 4 is a top plan view thereof;
FIG. 5 is a rear elevational view thereof; and
FIG. 6 is a left side elevational view thereof.

It is to be understood that the fragmentary representation of fabric extends throughout the entire rectangular areas in all of these figures wherein fabric is illustrated.

I claim:

The ornamental design for an aviator's bail-out oxygen tube connection unit, as shown.
